APPARATUS FOR DRYING AND SHAPING
THE SHOULDERS OF GARMENTSRobert J. Beede, Providence, R. I., assignor to
Pantex Pressing Machine, Inc., Central Falls,
R. I., a corporation of Delaware

Application April 4, 1938, Serial No. 200,002

5 Claims. (Cl. 223—70)

My present invention relates to improvements in garment pressing or shaping machines, and especially to garment pressing or shaping machines adapted to press or shape and dry the shoulders of coats. This application is a continuation in part of my application, S. N. 33,907, filed on July 30, 1935, allowed October 6, 1937, for Apparatus for drying and shaping the shoulders of garments.

10 The coats of summer clothing have little or no padding at the shoulders, and are commonly subjected to laundering or washing, and in some instances to dry cleaning. The usual purpose of the padding in shoulders of coats, as is well known, is to preserve or maintain the proper shape thereof, but since such padding is not usually provided in summer clothing it is difficult to properly shape the shoulders of the coats after laundering.

15 The principal general object of my present invention is to provide an apparatus adapted to receive the shoulders and adjacent parts of the sleeves of coats which have been laundered or cleaned, and to shape and dry the moist shoulders by a relatively simple and quick operation. In this connection the invention contemplates the provision of a pair of shoulder receiving and shaping devices, heated by any suitable means, so that the coats may be readily placed on said devices and then automatically subjected to the shaping and drying operation to effect a smooth and neat appearance.

20 A more specific object of the invention is to provide in a machine of the character mentioned shoulder shaping and drying devices which are normally in open or shoulder stretching and shaping position, and which must be manually closed or positioned to receive the shoulders and adjacent portions of the sleeves of coats; and which automatically assume said normal position properly stretching or shaping the shoulders and portions of the sleeves adjacent thereto without exerting manual force which might rip the seams or tear the cloth.

25 A further object of my invention is to provide in such a device means to properly grip the crotch or lower portion of the sleeve head adjacent the seam line to insure that the upper portion of the sleeve and adjacent parts of the coat, including the shoulder thereof, are evenly shaped and pressed.

30 A further object of my invention is to provide means capable of positively selectively gripping the crotches of sleeves of different sizes to selectively function to positively grip, shape and press

the sleeves and adjacent shoulder portions of different sized coats.

Another specific object of my invention resides in the provision of apparatus of the above type in which the pairs of shoulder shaping and drying devices are simultaneously or collectively operated although, if desired, may be individually operated.

The foregoing and other objects and advantages of the invention will become more apparent and will be pointed out during the course of the following detailed description of the accompanying drawings, in which:

Fig. 1 is a front elevation of a machine embodying my present invention with parts broken away and partially in section.

Fig. 2 is an enlarged vertical longitudinal sectional view through one of the shaping and drying members.

Fig. 3 is a view taken on the line 3—3 of Fig. 1 with portions of the base of the machine broken away.

Fig. 4 is a view taken on the line 4—4 of Fig. 2.

Fig. 5 is a central longitudinal vertical sectional view through the foot operated lever and parts associated therewith.

Fig. 6 is a perspective view of a collar used for limiting the movement of the foot operated lever.

Fig. 7 is a rear perspective view of the machine embodying my invention shown in Fig. 1.

Fig. 8 is a rear perspective view similar to Fig. 7, showing a coat mounted on the pressing members thereof, said pressing members being shown in the act of pressing the coat.

Fig. 9 is a side elevation of the top of my improved machine showing a jaw in closed position after the sleeve of the coat has been mounted thereon with a portion of the coat broken away to show the heated stationary pressing member and jaw.

Fig. 10 is a view similar to Fig. 9 after the lower jaw has dropped by gravity to draw the sleeve and adjacent parts of the coat against the outer surfaces of the heated stationary member.

Referring to the drawings the numeral 5 indicates the uprights or legs of the machine connected or coupled at their bottoms to supports 6 which rest on the floor, and at their tops to couplings 7 which support the table 8. In actual practice I preferably provide four of the uprights or supports 5, one at each corner of the machine, and connect the supports or uprights to each other along the front and back of the machine by rods 9 connected to couplings 10 on the bases 6, while the respective front and back up-

rights are connected along the sides of the machine by struts 11, the ends of which are connected to the bases 6 by pins 12.

On top of the table 8 are two couplings 13 alined 5 with each other longitudinally of the table and located adjacent the front thereof above openings 14. The couplings 13 are screw threaded to receive the threaded ends of pipes 15 and 16, and the pipes 16 are threaded into T joints 17 which 10 also receive pipes 18 communicating with the T coupling 19 also connected to a pipe 20 which, at its other end, is connected to an elbow joint 21. A pipe 22 is connected at one end to a valve 23 and leads at its other end to a source of discharge. 15 said pipe forming a part of the exhaust and drain line. The valve 23 is connected by pipe 24 to the elbow 21.

The steam which preferably serves as the heating medium, although other suitable heating media 20 may be used, is supplied through pipes 25 located within and concentric with the pipes 15 and 16 and connected at their lower ends to elbows 26 which are also connected to pipes 27, in turn connected to the T coupling 28 communicating 25 with the pipe 29 through which the steam is supplied.

The upper ends of the pipes 15 support the shaping and drying elements having threaded engagement therewith as indicated by the numeral 30 30. The pipes 15 and 25 also open into the tortuous chambers 31 within the upper members 32 of the shaping and drying elements. The steam supplied through the pipe 25 in the manner described circulates through the chamber 31 in the heads or 35 shaping members 32 and flows down through the pipes 15 with any water created by condensation to be ejected through the drain previously described.

The upper members 32 of the shaping and drying 40 elements are relatively narrow at their rear ends 34 and relatively broad at their front ends 35 and are curved on their tops and sides to snugly fit into the sleeves and the shoulders of coats placed thereover. The narrow ends 34 enter the 45 sleeves and facilitate positioning of the shoulder portions of the coats over the broader rounded ends 35.

Cooperating with the upper member 32 of the 50 drying and shaping element is a lower member 36 normally held in closed relation to the upper member or in the dash and dot line positions of Figs. 2 and 3 to facilitate insertion of the element into the sleeves of coats, and automatically operable after said insertion to assume the open 55 or full line position of Figs. 2 and 3 to effect smoothing of the shoulders and portions of the sleeves adjacent thereto during the drying and shaping operation.

The lower portion of the member 32 is provided 60 with brackets 37 secured in place by screws 38 and holding therebetween a shaft or pin 39. The forked ends 40 of a lever 41 are pivotally mounted on the pin or shaft 39. Also secured between the forked arms of the lever 41 is a pin 42 which 65 receives a coupling pivoted thereto, and connected to the upper end of an actuating rod 44, which is screw threaded into the coupling 43 as indicated at 45. The rear end of the member 36 is provided on its interior with spaced upstanding 70 ribs or lugs 46 which receive a plate 47 secured thereto as by means of screws 48. The front end of the plate 47 is provided with bosses or ears 49 through which extends a pin 50 on which the rear end of the lever 41 is pivotally connected as 75 at 51. The lower wall of the member 36 at its

front end is preferably rounded and engages a notch in the coupling 43 as indicated at 52, while the front end of the plate 47 extends across the rear end of the lever 41 as indicated at 53, the said plate 47 being provided with an opening 54 through which the rear end of the lever 41 extends. 5

The upper member 32 may be provided with threaded adjustable plugs 56 in its lower surface, one of which is adapted to be abutted by a cushioning pad 57 secured to the top of the plate 47 on the member 36 as by means of a screw 58 which engages through the said cushioning member between its side upstanding arms, said cushioning member being preferably of channel for- 15 mation.

Preferably there are two of the shaping and pressing elements each of the same construction, and each having connected thereto an operating rod 44 extending through an opening 60 in the 20 table 8. The lower ends of the rods 44 are connected or seated in sockets 61 on a transverse connecting part 62 of the foot operated lever, and preferably the said sockets are provided with rubber or other cushioning inserts 61' to receive the 25 lower ends of the rods 44. The sockets 61 are preferably arranged at the ends of the transverse connecting part 62 of the foot operated lever 63, the forward end of which is provided with a treadle T. The foot operated lever 63 is also provided on its bottom and intermediate its ends with grooves or channels 64 which receive or are seated on the rod 9 extending between opposite side uprights 5 of the frame. The said rod 9 constitutes the fulcrum for the lever 63. The foot 30 operated lever 63 is also provided intermediate the grooves or channels 64 with an opening receiving a collar 65, shown in detail in Figs. 5 and 6, and which limits the movement of the foot 35 lever 63. The collar 65 has a groove or opening 40 65' which also receives the rod 9, and also has laterally extending lugs or projections 65'' which are arranged within the grooves 64 of the foot 45 operated lever 63 when the parts are assembled. A set screw S locks the collar 65 to the rod 9 against rotational movement thereon so that the 50 foot operated lever 63 may be oscillated when the treadle T is depressed and released, the extent of movement of the lever being determined by the width of the notches 64 in which the extensions or lugs 65'' are disposed. It should be obvious that in one direction of movement of the lever 63 one side of the channel or groove 64 contacts one side of the lugs or extensions 65'', and vice versa. Obviously the positioning of the 55 collar 65 on the rod 9 is such as to bring the lugs or extensions 65'' within the notches or channels 64 when the treadle lever is placed in position.

As has already been mentioned the member 36 is normally in the full line or open position of 60 Figs. 2 and 3, due to the fact that the weight of the forward end thereof, including the plate 47 and supporting parts, swings said member 36 downwardly on the pivot 39 which forms the fulcrum for the lever 41. Hence the rods 44 are normally depressed, and the treadle T is normally elevated.

With the foregoing in mind, when it is desired 70 to shape and dry the shoulders of coats or similar garments it is simply necessary for the operator to step on the treadle T to elevate the rods 44 when the foot lever is rocked on its pivot 9 to elevate the sockets 61, whereby the couplings 43 raise the levers 41 and the members 36 carried thereby to the dot and dash line positions of 75 75.

Figs. 2 and 3, so that the pressing and shaping elements comprising the parts 32 and 36 are established in their closed positions and may readily receive the arm openings and shoulders 5 of coats placed thereon. It is then simply necessary for the operator to release the treadle T whereby the gravitation of the parts 36 to open position will stretch the portions of the sleeves and shoulders arranged over the parts 32 and 36 10 into smooth condition so that the heat passing through the chamber 31 and the smooth rounded surfaces of the members 32 will quickly shape and dry the sleeves and adjacent shoulder portions of the coats without the exertion of manual effort or 15 force which might tear the seams if not properly applied.

I have shown in Figs. 7-10 a slightly different embodiment of my invention employing means preferably comprising a roughened portion 70 extending a distance rearwardly from the front end of said jaw 36 to positively grip the crotch of the sleeve to draw the sleeve and adjacent portions of the coat against the outer surfaces of the heating stationary member 32, including the top 25 portion 72 thereof preferably arcuate in vertical section to fit the contour of the sleeve and the front end 74 thereof also preferably arcuate in horizontal section to fit the contour of the shoulder. While said means or roughened portion 70 30 may be of any shape, to positively grip the sleeve crotch at this point I preferably provide for this purpose a plurality of descending means of different heights extending a distance rearwardly from the front end of said jaw 36 to positively selectively grip the crotches of sleeves of different sizes on different descending portions thereof, and in my preferred embodiment said means of different heights preferably comprises a plurality of substantially concentric substantially circular descending steps 76.

Figs. 8-10 show the operation of my improved machine in use. The coat 80 is grasped by the operator so as to lie in the rear of the rearwardly projecting stationary members 32 with the sleeves 45 82 thereof substantially in line with said stationary members 32. The coat 80 is then drawn forwardly so that the upper portions of the sleeves or heads are inserted over the stationary members, the treadle T having first been depressed to raise 50 the jaws 36 into juxtaposition with the stationary members 32 to permit the sleeve heads 84 to be drawn over to surround said members 32 and jaws 36 then lying adjacent thereto. The coat is pulled forward until the sleeve seam lines 86 are substantially brought adjacent the front ends of the tops 55 72 of said stationary members 32 as shown in Fig. 9 and the sleeve crotches 88 adjacent the seam lines 86 are brought forward until each rests against a selected step 76 suitable for the size of 60 the sleeve as shown in Fig. 9. The foot is then raised from the treadle T permitting the lower jaws 36 to drop as shown in Fig. 10 and as the lower jaws drop they will positively grip the sleeve crotches 88 to draw the sleeves downwardly and 65 hence draw the opposite portions of the sleeve heads 84 against the upper surfaces 72 of the stationary members and the adjacent portions of the shoulders against the front surfaces 74 of the stationary members 36, the seam lines 86 substantially abutting the rounded front top ends 70 between said portions 72 and 74 to evenly draw the sleeves and adjacent portions of the coat against the outer surfaces of the top and front portions 72 and 74 of the heated stationary members 32 as 75 shown in Figs. 8 and 10.

It is apparent that sleeves of different sizes will have the sleeve crotches 88 therein brought adjacent different sized steps, the smaller the sleeve the more rearwardly step 76 contacted by said crotch.

Although I have shown and described a single operating foot lever for a pair of shoulder shaping and drying elements, it should be obvious that the part 62 may be divided if desired and the sockets 64 connected to individual foot levers to be separately operated. Of course the spacing between the shaping elements is such as to accommodate both shoulders of coats over a range of various sizes, that is, they are sufficiently close together to permit the coat shoulders to be properly positioned whether the coat be of small size or large size.

I have also found in actual operation that it is not necessary to provide for the intermittent supply of steam or other heating medium through the 20 elements 32 as in the case of many garment pressing machines, but that the heating medium or steam may continuously flow through the chamber 31 of each element and may be cut off by the hand operated valves in the supply pipes and drain 25 pipes above mentioned.

In the embodiment shown I have shown the treadle T in the front of the machine to be operated by the operator and with the enlarged ends of the stationary members 32 also at the front and I, therefore, employ the words "forwardly" and "rearwardly" and "front" and "rear" in the claims in reference to the specific structure shown although it is obvious that if desired the direction in which the stationary members 32 point relative 30 to the balance of the machine may be varied in use as desired. I employ the words "sleeve crotch" to signify the portion of the sleeve and coat adjacent the portion of the sleeve seam underneath the arm pit.

It is understood that my invention is not limited to the specific embodiment shown and that various deviations may be made therefrom without departing from the spirit and scope of the appended claims.

What I claim is:

1. A substantially horizontal stationary member having an enlarged end having its end and upper surfaces approximately at right angles to each other and shaped to correspond to the inner contour of the shoulder and upper sleeve portion of a coat, said member tapering therefrom to its rear end with a smooth unbroken surface, means for heating said member, a weighted tapered jaw pivoted at its front end to said stationary member near the enlarged end thereof and shaped to form, when in juxtaposition with the stationary member, substantially a circumferential continuation of its tapered portion, and releasable means to move said jaw into juxtaposition with the stationary member, whereby the upper portion of the sleeve of a coat may be drawn over the tapered portions of the stationary member and the jaw and the shoulder of the coat laid over the enlarged end of the stationary member, said jaw being so 50 constructed and arranged that when released it will draw the sleeve and adjacent parts of the coat against the outer surfaces of the heated stationary member.

2. A pair of substantially horizontal parallel 70 stationary members spaced to receive both sleeves of a coat at a time, each having an enlarged end having its end and upper surfaces approximately at right angles to each other and shaped to correspond to the inner contour of the shoulder and 75

upper sleeve portion of a coat, said member extending rearwardly therefrom to its rear end with a smooth unbroken surface, means for heating said members, a pair of weighted tapered jaws, 5 each pivoted at its front end to one of said stationary members near the enlarged end thereof and shaped to form, when in juxtaposition with its respective stationary member substantially a circumferential continuation thereof, and a 10 treadle arranged to move said jaws into juxtaposition with the stationary members, whereby the upper portions of the sleeves of a coat may be drawn over the rearwardly extending portions of the stationary members and the jaws and the 15 shoulders of the coat laid over the enlarged ends of the stationary members, said jaws being so constructed and so arranged that when the treadle is released the jaws will draw the sleeves and adjacent parts of the coat against the outer 20 surfaces of the heated stationary members.

3. A substantially horizontal stationary member having an enlarged end having its end and upper surfaces approximately at right angles to each other and shaped to correspond to the inner 25 contour of the shoulder and upper sleeve portion of a coat, said member extending rearwardly therefrom to its rear end with a smooth unbroken surface, means for heating said member, a weighted jaw pivoted at its front end to said stationary 30 member near the enlarged end thereof and shaped to form, when in juxtaposition with the stationary member substantially a circumferential continuation thereof, and releasable means to move said jaw into juxtaposition with the stationary member, whereby the upper portion of 35 the sleeve of a coat may be drawn over the rearwardly extending portion of the stationary member and the jaw and the shoulder of the coat laid over the enlarged end of the stationary member, said jaw being so constructed and arranged 40 that when released it will draw the sleeve and adjacent parts of the coat against the outer surfaces of the heated stationary member, said jaw having a plurality of substantially concentric 45 substantially circular descending steps extending a distance rearwardly from the front end thereof to positively selectively grip the crotches of sleeves of different sizes on a selected step to draw the sleeve and adjacent parts of the coat against the outer surfaces of the heated stationary member.

4. A substantially horizontal stationary member having an enlarged end having its end and upper surfaces approximately at right angles to each other and shaped to correspond to the inner 50 contour of the shoulder and upper sleeve portion

of a coat, said member extending rearwardly therefrom to its rear end with a smooth unbroken surface, means for heating said member, a weighted jaw pivoted at its front end to said stationary member near the enlarged end thereof and shaped to form, when in juxtaposition with the stationary member substantially a circumferential continuation thereof, and releasable means to move said jaw into juxtaposition with the stationary member, whereby the upper portion of the 10 sleeve of a coat may be drawn over the rearwardly extending portion of the stationary member and the jaw and the shoulder of the coat laid over the enlarged end of the stationary member, said jaw being so constructed and arranged that 15 when released it will draw the sleeve and adjacent parts of the coat against the outer surfaces of the heated stationary member, said jaw having descending means of different heights extending a distance rearwardly from the front 20 end thereof to positively selectively grip the crotches of sleeves of different sizes on selective portions thereof to draw the sleeve and adjacent parts of the coat against the outer surfaces of the heated stationary member. 25

5. A substantially horizontal stationary member having an enlarged end having its end and upper surfaces approximately at right angles to each other and shaped to correspond to the inner 30 contour of the shoulder and upper sleeve portion 35 of a coat, said member extending rearwardly therefrom to its rear end with a smooth unbroken surface, means for heating said member, a weighted jaw pivoted at its front end to said stationary member near the enlarged end thereof and shaped to form, when in juxtaposition with the stationary member substantially a circumferential continuation thereof, and releasable means to move said jaw into juxtaposition with the stationary member, whereby the upper portion of 40 the sleeve of a coat may be drawn over the rearwardly extending portion of the stationary member and the jaw and the shoulder of the coat laid over the enlarged end of the stationary member, said jaw being so constructed and arranged that when released it will draw the sleeve and adjacent parts of the coat against the outer 45 surfaces of the heated stationary member, said jaw having a roughened portion extending a distance rearwardly from the front end thereof to positively grip the crotch of the sleeve to draw 50 the sleeve and adjacent parts of the coat against the outer surfaces of the heated stationary member.

ROBERT J. BEEDE.
